UNITED STATES PATENT OFFICE

2,573,651

FORCED AIR FLOW AIR-HEATING FURNACE

Alonzo W. Ruff, York, Pa., assignor to Harvey-
Whipple Incorporated, Springfield, Mass., a cor-
poration of Massachusetts

Application June 23, 1949, Serial No. 100,921

10 Claims. (Cl. 126—110)

1

This invention relates to improvements in heating apparatus.

The principal object of the invention is the provision of heating apparatus which is not only adapted for installation in various positions but which is simple in form and compact as well as economical in operation.

According to certain novel features of the invention, the heating apparatus may be suspended from the ceiling or the like or set on its end or side thereby adapted for installation in various ways and in numerous locations.

According to other novel features of the invention, the heating apparatus is arranged and constructed for ready and easy accessibility to its components.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a longitudinal elevational view through heating apparatus embodying the novel features of the invention;

Fig. 2 is a sectional plan view substantially on the line 2—2 of Fig. 1;

Fig. 3 is a sectional view to explain certain features of the invention; and

Fig. 4 is a partial sectional view through cover plate 22.

Referring now to the drawings more in detail, the invention will be fully described.

A casing is provided which has front and rear walls 2 and 4, end walls 6 and 8 and upper and lower walls 10 and 12.

Any or all of the walls may be formed with depressions 14 and openings 16 with cover members 18 thereover as shown in Fig. 3. In Fig. 1 the rear and forward walls have covers 20 and the end walls 6 and 8 have covers or cover plates 22 and 24. It will be understood that the cover plates may be secured to the casing in any well known manner and may be of any desired form.

A combustion chamber 30 is provided adjacent the end wall 8 or the outlet end of the casing. Said chamber has opposite walls 32 and 34 which as in Fig. 1 converge to parallel walls 36. A rear wall 38 closes the rear side of the combustion chamber 30 and the end is closed by an end wall 40.

2

A plate 42 is removably secured to the forward side of the combustion chamber 30 and a forward wall 44 inclines away therefrom and connects with rear wall 40, see Fig. 2.

It will be noted that the combustion chamber tapers rearwardly from the forward or outlet end of the casing so as to provide a narrowing passageway for the products of combustion.

The plate 42 is provided with an opening 46 for an oil burner which is shown diagrammatically at 48 in Fig. 2. This oil burner is associated with wall 4 and said plate 42 and may be similar to that shown in application Serial Number 76,066 of February 12, 1949 which has been issued as Patent No. 2,527,503, dated October 24, 1950.

Air for combustion enters through inlets 50 in the outer end of the oil burner and is drawn therethrough and discharged together with fuel at the inner end within the combustion chamber, as will later appear. The combustion chamber may be provided with refractory 31 as is common practice and the burner may take various forms as may be desired.

Upper and lower hollow compartments 50 and 52 are provided at opposite sides of the combustion chamber and have inner walls 50' and 52' which are spaced from and follow the adjacent walls 36 of said combustion chamber.

Hollow connections 60 extend between adjacent walls 50' and 52' of the compartments and of the combustion chamber. A hollow connection 62 extends between the walls 50' and 52' of the compartments 50 and 52 which is disposed adjacent wall 44 of the combustion chamber, see Fig. 2.

Baffles such as 64 extend between upper and lower walls of compartments 50 and 52 and from rear walls 66 thereof forwardly to a point spaced from the forward ends of said compartments forming transverse passageways such as 68, see Fig. 2.

A hollow fan housing 70 is secured to the compartments and is preferably in the form shown in Fig. 1. A connection 72 extends from connection 62 to the housing 70, as shown in Fig. 2.

An air propeller 74 within the housing is carried by a shaft of a motor 76 which is disposed outside the casing and is supported by a platform 78.

An outlet connection 80 from the housing 70 extends outwardly of the casing and has a flue 82 connected thereto.

In operation air is drawn inwardly through the burner 48 for combustion. The products of com-

bustion travel rearwardly as indicated by arrows *a*, upwardly through connections 60 indicated by arrows *b* into compartments 50 and 52 and therealong and through passageways 68 as indicated by *c*. From the compartments 50 and 52 the products of combustion and gases are drawn through connections 62 and 72 to housing 70 from whence they are discharged through connection 80 to the flue 82 which may be connected to a stack.

It will be observed that the path of the products of combustion and gases traverse a circuitous route past numerous separate walls which are heated thereby so that air which is caused to flow relative to and wipe said walls is heated, as will appear.

A housing 90 is provided which has an inlet 92 and an outlet 94. This housing is mounted by mounting means 94 in the casing and said means is adapted to absorb vibrations, shock and resulting noise.

An air propeller 96 within the housing 90 is fixed to a shaft 98. Said shaft 98 has a pulley 100 fixed thereto which is connected by an endless driver 102 to a pulley 104 fixed on shaft 106 of a motor 108 which is supported on platform 78.

A conduit 110 tubular in form and preferably made from pliable material, such as canvas or the like, has one end connected to the discharge end 94 of the housing 90. Its other end is supported by a member or members 112 fixed to the casing.

The cover member 24 at the outlet end of the casing is provided with an outlet 114 which may be connected to an air distributing system of any desired type.

A baffle 118 at the outlet end of the housing has an intermediate portion 120 extending around and spaced from the combustion chamber and side parts spaced therefrom. An outlet 122 of the baffle extends into the outlet 114, as shown.

As stated, the apparatus may be installed by suspending it from a ceiling or it may be set on its end. A cover plate or portion thereof at the rear or end of the casing is removed or other means is provided for admitting circulating air for the blower. Suitable circuit control means for the motors 76 and 108 is provided for operation of the apparatus so that the desired operation is obtained. Means for admitting air into the rear end of the casing according to the form of the invention shown includes a plurality of openings 23 in plate 22, as shown in Fig. 4.

With the fan in operation, and with fuel supplied the burner 48 and ignition means in operation the products of combustion are drawn by the air propeller 74 from the combustion chamber in opposite directions into and through the compartments 50 and 52 and into the housing 70. The hot gases are forced from the housing outwardly through connection 80 into the flue 82 which may be connected to the stack.

The circuitous movement of hot gases heats the numerous walls of the combustion chamber and compartments for heating air delivered by the blower.

Air discharged from the blower flows through connection 110 past the walls of the compartments 50 and 52 and combustion chamber and between the spaced adjacent walls of the said compartments and chamber. The greater amount of air is directed by member 118 upwardly and around the combustion chamber and out outlet 114. In this way the numerous walls of the com-

bustion chamber and compartments are wiped by the air for the efficient transfer of heat.

A minor portion of the air flows around outside the member 118 and outwardly between members 114 and 122 and is effective for cooling the end portion of the casing and carrying heat from the member 118 outwardly.

It will be noted that the combustion chamber and compartments are spaced from the casing walls in Fig. 2, but in some cases it may be desirable to eliminate said space.

The housing or scroll 70 is welded to the heat exchanger to provide a gas tight connection and in such a way as to seal the combustion gas circuits and flow of air. The said scroll is in the path of air discharge from the blower whereby there is heat transfer from the scroll as well as from the combustion chamber and compartments.

The blower casing 94 is connected to the casing by isolation mountings one of the compression type and the other of shear type so that regardless of the positioning of the apparatus vibrations and resulting noise is eliminated.

The hub of the suction fan is provided with an insulating bushing to retard heat transfer to the said shaft and motor.

The controls for the blower and fan motors may be arranged for any desired cycle of operation thereof. Operation of the blower motor may be delayed relative to the operation of the fan. They may operate simultaneously, the blower may be operated while the fan is inoperative all to the end that the apparatus may be operated to suit various conditions and requirements.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. Heating apparatus comprising in combination, a casing having an air outlet at an outlet end thereof, a combustion chamber disposed in said outlet end of the casing having a rear portion tapering inwardly of the casing away from said outlet, housings adjacent and spaced from opposite sides of the rear portion of said combustion chamber, connections between the rear portion of said combustion chamber and housings, a suction device having a discharge, connections between said housings and suction device whereby products of combustion are drawn from said combustion chamber through said housings and discharged from said discharge, said casing provided with air inlet means for a blower, and a blower device rearwardly of said combustion chamber and housings for projecting air forwardly past and between said combustion chamber and housings and outwardly of said outlet.

2. Heating apparatus comprising in combination, a casing having an inlet end and an outlet end, said outlet end provided with an air outlet for connection to an air system, a combustion chamber for an oil burner in the outlet end of said casing having rearwardly converging opposite walls extending inwardly of the casing away from said outlet and terminating in substantially par-

alled end portions providing a chamber which narrows from its forward end rearwardly, separate housings spaced from opposite sides of said combustion chamber having inner walls substantially parallel to said end portions and converging walls of the combustion chamber, hollow connections between said housings and end wall portions of the combustion chamber and a hollow connection between said housings, a suction device within said casing having a suction inlet connected to said last named connection and provided with a discharge extending through said casing, said inlet end of the casing provided with an air inlet disposed rearwardly of said combustion chamber and separate housings for the flow of air therapst from said inlet to said air outlet.

3. Heating apparatus comprising in combination, a casing having an outlet end provided with an air outlet for connection to an air system, a combustion chamber for an oil burner in the outlet end of said casing having rearwardly converging opposite walls extending inwardly of the casing away from said outlet and terminating in substantially parallel end portions providing a chamber which narrows from its forward end rearwardly, separate housings spaced from opposite sides of said combustion chamber having inner walls substantially parallel to said end portions and converging walls of the combustion chamber, hollow connections between said housings and end wall portions of the combustion chamber and a hollow connection between said housings, a suction device within said casing having a suction inlet connected to said last named connection and provided with a discharge extending through said casing, said casing provided with air inlet means for a blower, and a blower within said casing rearwardly of said chamber and housings having an inlet and provided with a discharge for directing air towards and past said chamber and housings and therebetween and out the outlet of the casing.

4. Heating apparatus comprising in combination, a casing having an outlet end provided with an air outlet for connection to an air system, a combustion chamber for an oil burner in the outlet end of said casing having rearwardly converging opposite walls extending inwardly of the casing away from said outlet and terminating in substantially parallel end portions providing a chamber which narrows from its forward end rearwardly, separate housings spaced from opposite sides of said combustion chamber having inner walls substantially parallel to said end portions and converging walls of the combustion chamber, hollow connections between said housings and end wall portions of the combustion chamber and a hollow connection between said housings, a suction device within said casing having a suction inlet connected to said last named connection and provided with a discharge extending through said casing, said casing provided with air inlet means for a blower, and a blower within said casing rearwardly of said chamber and housings having an inlet and provided with a discharge for directing air towards and past said chamber and housings and therebetween and out the outlet of the casing and operating means therefor outside said casing, operating means for said suction device and for said blower, and operative connections between said operating means and said suction device and blower.

5. Heating apparatus comprising in combination, a casing having an outlet end provided with

an air outlet for connection to an air system, a combustion chamber for an oil burner in the outlet end of said casing having rearwardly converging opposite walls extending inwardly of the casing away from said outlet and terminating in substantially parallel end portions providing a chamber which narrows from its forward end rearwardly, separate housings spaced from opposite sides of said combustion chamber having inner walls substantially parallel to said end portions and converging walls of the combustion chamber, hollow connections between said housings and end wall portions of the combustion chamber and a hollow connection between said housings, a suction device within said casing having a suction inlet connected to said last named connection and provided with a discharge extending through said casing, said casing provided with air inlet means for a blower, a blower within said casing rearwardly of said chamber and housings having an inlet and provided with a discharge for directing air towards and past said chamber and housings and therebetween and out the outlet of the casing and operating means therefor outside said casing, and operative connections between said operating means and said suction device and blower, a baffle in the outlet end of the casing extending around and spaced from the end of the combustion chamber and adjacent rearwardly extending walls thereof and from adjacent walls of the casing having an outlet of relatively less dimensions than those of said air outlet whereby air from said blower is directed around said combustion chamber to said outlet and in relatively less amount around said baffle and out said outlet,

6. Unitary heating apparatus comprising in combination, a casing having upper and lower and side and opposite end walls, one of said end walls provided with an air outlet of certain area, a combustion chamber within the casing having an end wall spaced inwardly and rearwardly from said air outlet and curving upwardly and away from said outlet merging in upper and lower walls which converge rearwardly and terminate in elongated upper and lower rearwardly extending and spaced upper and lower walls, vertical side walls secured to said end and upper and lower walls and an end wall secured to said side and upper and lower walls, closed housings within said casing above and below the upper and lower walls of said chamber having elongated outer and inner and side and end walls, said inner walls of said housings being spaced from and substantially parallel to the upper and lower parallel and converging walls of the combustion chamber, hollow connections extending between the inner walls of said housings and upper and lower walls of said combustion chamber, outer and side walls of said housing being spaced from adjacent walls of the casing, a hollow connection extending between inner walls of said housings, said casing provided with an air inlet means for a blower, an air blower in said casing adjacent the other end wall thereof having a discharge outlet for directing air to said air outlet past and between said housings and combustion chamber and casing walls, a suction device within said casing having a suction inlet and a discharge extending through a side wall of said casing, a hollow connection connecting said suction inlet and said last-named hollow connections, separate driving means for said blower and suction device disposed outside said casing, and driving connections between said

driving means and said blower and suction means extending through said casing.

7. Unitary heating apparatus comprising in combination, a casing having upper and lower and side and opposite end walls, one of said end walls provided with an air outlet of certain area, a combustion chamber within the casing having an end wall spaced inwardly and rearwardly from said air outlet and curving upwardly and away from said outlet merging in upper and lower walls which converge rearwardly and terminate in elongated upper and lower rearwardly extending and spaced upper and lower walls, vertical side walls secured to said end and upper and lower walls and an end wall secured to said side and upper and lower walls, closed housings within said casing above and below the upper and lower walls of said chamber having elongated outer and inner and side and end walls, said inner walls of said housings being spaced from and substantially parallel to the upper and lower parallel and converging walls of the combustion chamber, hollow connections extending between the inner walls of said housings and upper and lower walls of said combustion chamber, outer and side walls of said housing being spaced from adjacent walls of the casing, a hollow connection extending between inner walls of said housings, said casing provided with air inlet means for a blower, an air blower in said casing adjacent the other end wall thereof having a discharge outlet for directing air to said air outlet past and between said housings and combustion chamber and casing walls, a suction device within said casing having a suction inlet and a discharge extending through a side wall of said casing, a hollow connection connecting said suction inlet and said last-named hollow connections, separate driving means for said blower and suction device disposed outside said casing, and driving connections between said driving means and said blower and suction means extending through said casing, and a baffle disposed between and spaced from said one wall of the casing and curved end wall of the combustion chamber having an air outlet of relatively less area than the air outlet of the casing and extending thereinto.

8. Heating apparatus comprising in combination, a casing having an air outlet, a combustion chamber disposed in the air outlet end of said casing and having a rear portion tapering inwardly of the casing away from the outlet, housings adjacent to and spaced from opposite sides of the rear portion of said combustion chamber, connections between the rear portion of said combustion chamber and housings, a suction device having a discharge, connections between said housings and suction device whereby products of combustion are drawn from said combustion chamber through said housings and discharged from the discharge, said casing provided with air inlet means for a blower, and a blower device rearwardly of said combustion chamber and housings for projecting air forwardly past and between said combustion chamber and housings and outwardly of the air outlet.

9. Heating apparatus comprising in combina-

tion, a casing having an inlet end and an outlet end, said outlet end provided with an air outlet for connection to an air system, a combustion chamber for an oil burner in the outlet end of said casing having rearwardly converging opposite walls extending inwardly of the said casing away from the outlet and terminating in substantially parallel end portions providing a chamber which narrows from its forward end rearwardly, separate housings spaced from opposite sides of said combustion chamber having inner walls substantially parallel to the end portions and converging walls of said combustion chamber, hollow connection between said housings and end wall portions of said combustion chamber and a hollow connection between said housings, a suction device within said casing having a suction inlet connected to said last named connection and provided with a discharge extending through said casing, said inlet end of the casing provided with an air inlet disposed rearwardly of said combustion chamber and separate housings for the flow of air therewith from said inlet to said air outlet.

10. Oil burner apparatus comprising in combination, a casing having an outlet and provided with an air outlet for connection to an air system, a combustion chamber for the oil burner in the outlet end of said casing having rearwardly converging opposite walls extending inwardly of said casing away from the outlet and terminating in substantially parallel end portions providing a chamber which narrows from its forward end rearwardly, separate housings spaced from opposite sides of said combustion chamber having inner walls substantially parallel to the end portions and converging walls of said combustion chamber, hollow connections between said housings and end wall portions of said combustion chamber and a hollow connection between said housings, a suction device within said casing having a suction inlet connected to said last named connection and provided with a discharge extending through said casing, said casing provided with air outlet means for a blower, and a blower within said casing rearwardly of said chamber and housings having an inlet and provided with a discharge for directing air towards and past said chamber and housings and therebetween and out the outlet of said casing.
